United States Patent Office

OTIS SHEPARD, OF ALTON, ILLINOIS.

Letters Patent No. 66,643, dated July 9, 1867.

IMPROVED BOOT-JACK, WRENCH, AND NAIL-PULL.

The Schedule referred to in these Letters Patent and making part of the same.

TO ALL WHOM IT MAY CONCERN:

Be it known that I, OTIS SHEPARD, of Alton, Madison county, Illinois, have invented a new and improved combined Boot-Jack, Wrench, etc.; and I do hereby declare that the following is a full, clear, and exact description thereof, which will enable others skilled in the art to make and use the same, reference being had to the accompanying drawings forming part of this specification.

The present invention relates to a novel construction of a boot-jack, whereby it can be used as a wrench, a tack or nail-drawer or extractor, a bolt-drawer, a saw-set, and a wrench for screwing off nuts to wagon-axles.

In the accompanying plate of drawings my combined boot-jack, wrench, etc., is illustrated—

Figure 1 being a plan or top view of the same, and

Figure 2 a central longitudinal vertical section.

Similar letters of reference indicate corresponding parts.

A, in the drawings, represents a boot-jack, having jaws, B, for the heel to the boot, which jaws, at their outer ends, C, are made of a prong or claw-shape, so that they can be used for extracting or drawing out tacks, nails, etc. The sides E and end F of the main portion of the boot-jack are cut out at various points into square-shaped notches D, of various sizes, suitable for nuts and bolt-heads, of varying sizes, thus constituting a wrench; and at the points G of the boot-jack slits H are made, which can be used as a means of setting the teeth of saw-blades. H' the prop or support for the boot-jack, which is made of suitable shape for turning on and off nuts to wagon-axles.

I claim as new, and desire to secure by Letters Patent—

As a new article of manufacture a boot-jack, provided with the tack-extractor e, wrenches D upon its sides E and end F, saw-sets H, and wagon-wrench I in the support H', as herein shown and described.

The above specification of my invention signed by me this 18th day of February, 1867.

OTIS SHEPARD.
